UNITED STATES PATENT OFFICE.

FREDERICK J. GIVEN, OF EAST ORANGE, NEW JERSEY, ASSIGNOR TO WESTERN ELECTRIC COMPANY, INCORPORATED, OF NEW YORK, N. Y., A CORPORATION OF NEW YORK.

INDUCTANCE COIL.

Application filed June 30, 1923. Serial No. 648,702.

To all whom it may concern:

Be it known that I, FREDERICK J. GIVEN, a citizen of the United States, residing at East Orange, in the county of Essex, State of New Jersey, have invented certain new and useful Improvements in Inductance Coils, of which the following is a full, clear, concise, and exact description.

This invention relates to inductance coils. An object of this invention is to provide a unitary structure having a plurality of inductance windings, the mutual inductance between which is substantially zero.

One form of this invention hereinafter described in detail comprises a hollow ring-shaped core forming a shell structure about an inner winding, at the same time forming a toroidal core for an outer winding. Since these two windings have their turns at right angles to each other, it follows that the mutual inductance between them is substantially zero.

Such a unitary structure is capable of many uses in telephone or other signaling systems, the coils being capable of use, for example, in loading units or loading simultaneously phantom and side circuits or as inductances in filters or other places where the mutual inductance between the coils should be negligible.

Fig. 1 represents a plan view of a toroidal shaped device having its windings arranged in accordance with this invention; Fig. 2 is a sectional view of the device of Fig. 1; Fig. 3 represents this invention embodied in an inductance device of the air core type; Fig. 4 represents an electric wave filter, the inductance coils of which may be constructed in accordance with this invention; and Fig. 5 illustrates how a plurality of the devices of this invention may be arranged to form a filter.

Referring to the form of this invention disclosed in Figs. 1 and 2, a toroidal shaped member 6 is disclosed in which a suitable winding 7 of a plurality of layers is embedded. The toroid 6 may be of any suitable magnetic material such as iron dust core material and may comprise two annular rings, the opposing faces of which are grooved to provide the necessary space for the coil 7. The two sections of the toroid may be held together by suitable bolts such as at the points 8, 9 and 10.

After the winding 7 has been embedded in

the iron dust core material and the two halves of the toroid have been clamped together, an additional winding 11 is wound in a plurality of turns or layers with a uniform distribution around the entire surface 60 of the toroid.

Due to the fact that the planes of the turns of windings 7 and 11 are mutually at right angles, the mutual inductance existing between the two windings 7 and 11 is substantially zero. If the winding 7 is embedded in such a position in the core that the surface of the core at right angles to the winding follows substantially the path of a line of force around the winding, the type of coil of Fig. 2 has substantially no external magnetic field, so that the coils 7 and 11 may be placed adjacent other devices of a similar type with a resulting economy both of material and space. A plurality of inductance devices such as that shown in Fig. 2 may be employed, for example, in the electric wave filter of the type shown in Fig. 4. The filter shown therein is of the low-pass type of a plurality of sections comprising series inductances 12 to 17, and shunt capacities 18 to 22. The inductance elements of such a filter must be carefully designed in order to insure the proper frequency transmission characteristic, and especially when the filter is of the type shown in Fig. 4, there must be no mutual inductance between the separate inductance elements. The inductance device of Fig. 2 may therefore be safely employed in such a filter in which winding 7 may be used as inductance 12, winding 11 as inductance 13 and similar windings from similar structures may be employed for the remaining inductances of the filter. Since the same core material serves for both windings 7 as well as winding 11 and since the arrangement disclosed has little or no external magnetic field it follows that the use of the device in electric wave filters and the like results in an economy of both material and space.

In case the windings 7 and 11 of Fig. 2 are employed in independent circuits such that different alternating currents would be flowing through the two windings, a small amount of cross-talk between the two windings has been observed in some cases but this cross-talk may be substantially reduced by creating a counteracting mutual induc-

tance in series with the solenoidal winding by winding one of the leads 30 of winding 7 about the toroid in the proper direction which may be in the same or opposite direction when compared to the turns of winding 11.

In case the two windings of the unitary inductance device are to be employed in a system in which coils with external fields are 10 permissible, a combination coil using an air or fibre core may be employed. Such a combination is shown in Fig. 3 in which a spool 24 of insulating material is employed instead of magnetic material for separating and supporting the two windings. The solenoidal winding 25 is wound on the spool in the usual manner after which the toroidal winding 26 is uniformly wound around the entire surface of the resulting toroid. Such a combination coil while having an external magnetic field will have substantially no mutual inductance between the two windings since the planes of the turns are maintained mutually at right angles. In one particular 15 combination coil constructed in accordance with Fig. 3, the coefficient coupling between the winding was found to be approximately .07% which is for all practical purposes negligible. Cross-talk between the two 20 windings was very small and could be reduced practically to zero by bringing one of the leads 27 of the solenoidal winding part of the way around the circumference of the coil thereby counteracting the progression 25 effect of the toroidal winding. Since the core in Fig. 3 is of air, no modulation, of course, occurs between the currents flowing in the two windings. No appreciable effect in the 30 constants of either winding due to the presence of the other winding was noted. This was in part due to the fact that a stranded conductor was used in both windings, thereby minimizing any current losses.

Fig. 5 shows how three combination coils 31, 32 and 33 of the type of Fig. 3 may be arranged mutually at right angles so that there will be no mutual inductance effects between the combination coils. The six windings of devices 31, 32 and 33 may 35 therefore be employed as the six inductances 12 to 17 of Fig. 4 without danger of interference between the coils. A considerable

saving of space results from the arrangement of the devices as in Fig. 5 since the devices may be mounted in close proximity to each other as long as they are kept at right angles to each other.

It is to be understood that various modifications of this invention may be made without departing in anywise from the spirit of this invention as defined in the appended claims.

What is claimed is:

1. An inductance device comprising a solenoidal winding, a form for supporting said winding and a second winding wound around said form and said first winding, said second winding having its turns substantially at right angles to the turns of said first winding and being substantially uniformly distributed over the entire external surface of said form and said first winding.

2. An inductance device comprising a toroidal core, a solenoidal winding embedded in said core, and a second winding wound around said core, and having its turns at right angles to the turns of said first winding, the turns of said second winding being uniformly distributed over the surface of said core.

3. An inductance device comprising a toroidal core of iron dust material, a solenoidal winding embedded in said core in a position arranged to give substantially no external field outside of said core for said winding, and a toroidal winding wound around said core and having its turns at right angles to the turns of said first winding, the turns of said second winding being uniformly distributed over the core.

4. An inductance device comprising a solenoidal winding, a form for supporting said winding, and a second winding wound around said form and said first winding, and having its turns substantially at right angles to the turns of said first winding, and a conductor connected to said first winding and wound around said form and said first winding in a plane at right angles to the turns of said first winding.

In witness whereof, I hereunto subscribe my name this 25th day of June A. D., 1923.

FREDERICK J. GIVEN.
